SAFETY RAIL FASTENING

Jacob Rush Snyder, Cleveland, Ohio

Application June 29, 1945, Serial No. 602,189

11 Claims. (Cl. 238—349)

1

This invention relates to rail fastenings of the kind embodying a resilient clamp or plate for yieldingly holding the rail against a support and, as one of its objects, aims to provide an improved fastening of this character which will hold the rail on the support in a safer and more satisfactory manner than the rail fastenings heretofore provided.

Another object of the present invention is to provide an improved rail fastening of the character mentioned, in which an insert or guard member used in conjunction with the clamp serves as a safety means for holding the rail on the support in the event of breaking of the clamp and as a means for limiting the initial flexing of the clamp, and wherein the insert accomplishes these functions without interference with a normal flexing of the clamp such as usually takes place during the passage of trains over the rail.

A further object of the invention is to provide an improved fastening of the character referred to, wherein the insert extends through the opening of the clamp and is engaged by the holding portion or head of the fastener as a spacer or stop for limiting the initial flexing of the clamp by the fastener.

The invention can be further briefly summarized as consisting in certain novel combinations and arrangements of parts hereinafter described and particularly set out in the appended claims.

In the accompanying sheets of drawings,

Fig. 1 is a top plan view, with portions in section, showing a rail fastening embodying the present invention.

Fig. 2 is a transverse sectional view taken through the fastening on line 2—2 of Fig. 1.

Fig. 3 is a detail sectional plan view showing the shape of the opening of the tie plate and with the fastener and insert disposed in the opening.

Fig. 4 is a plan view similar to Fig. 1 but showing a modified form of rail fastening embodying the present invention.

Fig. 5 is a partial transverse sectional view taken on line 5—5 of Fig. 4.

Fig. 6 is a detailed sectional view, on an enlarged scale, taken substantially on line 6—6 of Fig. 4 and further illustrating the locking feature for preventing accidental loosening of the fastening, and

Fig. 7 is a side elevation showing the guard member of the rail fastenings of Figs. 1 and 2 in detached relation.

The embodiment of the invention illustrated in Figs. 1 and 2 provides a fastening for yieldingly holding a rail 10 against a support which is here shown as being a tie plate 11 resting on a conventional wooden tie 12. The rail 10 is of a conventional construction which includes the usual head and web portions 10a and 10b and a laterally extending base flange 13 which is seated on the tie plate.

The tie plate 11 is here shown as comprising a

2

rectangular metal plate having upstanding rail-gauging integral shoulders or ribs 14 extending thereacross for cooperation with the edges of the base flange 13, although the present invention is equally applicable to rail fastenings in which these shoulders have been omitted from the tie plate. The tie plate is provided with a pair of diagonally disposed openings 15 which are used in the improved fastening and which are of a special shape. Except for the special shape of the diagonally disposed openings 15 the tie plate 11 is otherwise of a conventional form having a plurality of substantially square openings 16 therein of a size to accommodate conventional cut spikes. In the particular rail plate here shown the portion 11a upon which the base flange 13 of the rail is seated is tapered in thickness so that the rail will be supported in a position slightly inclined from the true vertical.

20 As shown in Fig. 3, each of the openings 15 of the tie plate consists of a substantially rectangular portion 15a which extends through the shoulder 14 and a substantially circular portion 15b which is located laterally outwardly of the portion 15a and communicates with the latter. A tie plate having the special openings 15 therein can be obtained by taking a tie plate of a conventional form having the above mentioned square spike opening 16 therein, and boring or otherwise forming the opening portions 15b in the tie plate adjacent a diagonally disposed pair of the square openings.

25 In addition to the rail support, which in this instance is formed by the tie plate 11 and the tie 12, the fastening includes the resilient clamp member 18, a fastener 19 and a rail guard or insert 20. The clamp member 18, which is also referred to herein merely as a clamp, is preferably in the form of a corrugated resilient metal plate 30 having bearing portions 21 and 22 at or adjacent its ends and which bear respectively on the rail flange 13 and the tie plate 11. The intermediate portion of the clamp bridges over the shoulder 14 of the tie plate and includes an upwardly bowed portion 23 with which the fastener 19 cooperates. The intermediate portion of the clamp is provided with an opening 24 which overlies the opening 15 of the tie plate and accommodates the fastener 19 and also the insert or guard member 20 in a manner which will be further explained hereinafter.

35 The fastener 19 is here shown as being a screw spike which serves very well when the fastening being formed includes the wooden tie 12. The screw spike may be of a conventional form having a threaded stem 25 extending into a preformed opening or bore 26 of the tie and also having a head 27 providing on the underside thereof a clamping face or shoulder 28 which engages the upper side of the intermediate portion 23 of the clamp 18. As shown in Fig. 3 40 of the drawings the stem of the fastener 19 ex-

tends through the circular portion 15b of the tie plate opening 15.

The rail guard or insert 20 is an important element of the improved fastening and is here shown in the form of a headed pin having a stem or body portion 30 of a substantially square cross-section which extends into or through the square portion 15a of the tie plate opening 15. The insert also has a laterally inwardly extending holding portion or lug 31 which overhangs the rail flange 13 and serves to retain the rail on the tie plate in the event of breaking of the resilient clamp 18. The insert 20 also serves the important function of acting as a spacer or stop for limiting the extent to which the spike 19 is driven into the tie, and hence, the initial flexing of the resilient clamp 18.

In the form of the fastening illustrated in Figs. 1 and 2 the upper portion of the insert 20 forms a spacer between the clamping surface 28 of the head of the fastener 19 and the upstanding shoulder 14 of the tie plate 11. To this end the insert is provided with oppositely extending integral lateral projections or lugs 32 which rest on the top of the shoulder 14 of the tie plate as shown in the drawings. The side of the insert which is disposed adjacent or against the stem of the spike 19 is of a recessed or concave contour, as indicated at 33, so as to provide a larger bearing surface and a centering cooperation between the insert and the stem of the spike. When the improved fastening embodies a tie plate from which one or both of the shoulders 14 have been omitted the insert 20 also serves as a rail gauging means by reason of the fact that the body portion of the insert is of a width or thickness to substantially fill the intervening space between the edge of the rail flange 13 and the stem of the spike 19.

It should be explained at this point that the opening 24 of the clamp 18 is preferably in the form of a slot as here shown. In assembling the improved rail fastening the spike 19 is inserted through the overlying openings of the clamp 18 and the tie plate 11 and is screwed part way into the tie 12. The clamp 18 is then shifted laterally toward the rail and relative to the partially driven spike to the extent permitted by the slot 24. The size and shape of the slot 24 are such that when the clamp is in this inwardly displaced position the insert 20 can be dropped or inserted into the tie plate opening through the slot of the clamp. In thus moving the insert into position between the edge of the rail flange and the stem of the spike, the lower end of the insert enters the square section 15a of the tie plate opening 15 and the projections 32 of the insert engage and rest upon the top of the shoulder 14 at opposite sides of the tie plate opening.

After the insert 20 has been thus moved into position the clamp 18 is shifted in the opposite or outward direction as far as is permitted by the insert, that is, to the position in which the clamp is shown in Fig. 2. The spike 19 is then driven further into the tie 12 to the fully driven position shown in the drawings. During movement of the spike 19 to its fully driven position, the shoulder 28 of the spike head 27 engages the upper surface of the intermediate portion 23 of the clamp and subjects the clamp to an initial flexing causing the ends thereof to press against the rail flange and tie plate. When the shoulder 28 of the spike engages the upper end of the insert 20 the spike will have been driven

to the desired extent and a further or excessive initial flexing of the clamp will be prevented.

It should be understood that instead of following the above-described procedure, the fastening can be assembled by first placing the clamp 18 and insert 20 in position on the tie plate 11 and then screwing the spike into the tie 12 the distance permitted by the insert. When the rail is to be removed it is only necessary to unscrew the spike part-way, remove the insert 20 and then swing the clamp on the spike through approximately 180° to thereby disengage the clamp from the rail flange.

It is important to note in connection with this improved fastening that the upper portion of the insert 20 extends through the opening 24 of the clamp so that the insert can be engaged by the shoulder 28 of the spike. The size and shape of the opening 24 are such as to accommodate the upper portion of the insert for this purpose and such that a subsequent relatively free flexing of the clamp can take place without interference with any portion of the insert. In its fully assembled position of the clamp 18 the inner end 24a of the clamp opening engages the inner end of the overhanging lug 31 of the insert and this prevents unintentional shifting of the clamp in an outward direction during the subsequent use of the fastening. The lug 31 and the projections 32 of the insert also cooperate with the edges of the clamp opening 24 for preventing unintentional swinging of the clamp 18 about the stem of the spike 19.

The rail fastening illustrated in Figs. 4, 5 and 6 of the drawings is similar to the fastening described above in detail in connection with Figs. 1 to 3 inclusive but in the modified fastening the projections 32 have been omitted from the insert or rail guard 35. In this case the lower end 40 of the insert seats upon the wooden tie 36 instead of on the tie plate 11 but in other respects the insert 35 is similar to the insert 20 and accomplishes the same functions as in the fastening previously described herein. The insert 35 will of course be of a length such that it will limit the driving of the spike 19 into the tie 36 when the clamp 37 has been flexed to the desired extent. When the projections 32 are omitted the clamp opening 38 can be of the shape shown in Fig. 4, that is to say, it can have a square portion 38a through which the insert 35 extends and a rounded slot portion 38b for the spike 19.

In rail fastenings of the kind herein disclosed it is desirable to prevent loosening of the spike 19 and in Figs. 4, 5 and 6 I have shown a locking or holding means for this purpose. This locking means comprises upstanding tooth-like elements 40 formed on the upper surface of the intermediate portion of the clamp 37 and which engage the underside or clamping surface 28 of the head of the spike. The metal of the clamp 37 is usually hardened in obtaining the desired resilient characteristic of the clamp and the projections 40, which are suitably formed as an integral part of the clamp, are therefore harder than the metal of the spike 19.

When the resilient clamp 37 has been flexed by the spike 19 the clamp will react to press or indent the projections 40 into the shoulder 28 of the spike. This indenting of the projections 40 into the spike may be accomplished only partially during the forming or assembling of the fastening but the subsequent flexing of the clamp, during passing of trains over the rail, will result in

the projections being indented for substantially their full height into the spike. When the projections 40 have been thus indented into the clamping surface 28 of the spike they will effectively hold the spike against turning in a direction to permit loosening of the fastening.

As shown in Fig. 4 the projections 40 are located on opposite sides of the opening 38 of the clamp and preferably on a line which is substantially coincident with a diameter of the stem of the spike 19. It should be understood that the projections 40 can also be embodied in the rail fastening illustrated herein in Figs. 1 to 3 inclusive.

It has been mentioned above that the openings 18 of the tie plate 11 are disposed in a diagonal relation. An advantage is obtained for this relative position for these openings because after a fastening has been in use for a considerable period of time the portions of the tie into which the screw spikes 19 extend may become weakened and by substituting a tie plate having these openings located on the opposite diagonal, the openings will overlie sound and unused portions of the tie.

From the foregoing description and the accompanying drawings it will now be readily understood that the present invention provides an improved rail fastening of the kind embodying a resilient clamp and which fastening is rendered safer and more satisfactory by the use of a novel insert or rail guard therein.

Although my improved rail fastenings have been illustrated and described herein in considerable detail it should be understood that the invention is not to be regarded as being correspondingly limited in scope since it is intended to include all changes and modifications coming within the spirit of the invention and the scope of the appended claims.

Having thus described my invention, I claim:

1. In a rail fastening of the type embodying a resilient plate overlapping a flange of the rail and an adjustable fastener extending through an opening of the plate, and having a head or the like engaging the top of said plate, a rail guard comprising a spacer for limiting the flexing of said plate by the fastener, said rail guard extending through the opening of the plate so as to be clampingly engaged directly by the head of the fastener and having a holding portion overlying said rail flange, said opening of the plate permitting flexing of said plate without interference by said rail guard.

2. In a rail fastening, a support, a rail on said support and having a base flange, a resilient rail-holding clamp member having portions bearing upon said support and flange and also having an opening therein between said portions, a driven fastener extending through said opening for connecting the clamp member with said support and holding the clamp member in a flexed condition, said fastener being adjustable relative to said support for varying the extent to which said clamp member is initially flexed by the fastener, and a second member cooperating with said fastener during the driving thereof for limiting the initial flexing of the clamp member by the fastener and having a rail-retaining portion extending over said flange, said second member having a portion thereof extending into the opening of said clamp member and said opening being of a size and shape to permit flexing of the clamp member without interference with said second member.

3. In a rail fastening, a wood tie, a tie plate on said tie and having an opening therein, a rail on said tie plate and having a base flange, a resilient rail-holding clamp member having its ends bearing respectively on said tie plate and flange and also having an opening therein between said ends and overlying the opening of the tie plate, a screw spike extending through said openings into the tie and having a head engaging the upper side of the clamp member for holding the latter in a flexed condition against said tie plate and flange, and a second member disposed in the opening of the tie plate and engaged by the underside of said head for limiting the initial flexing of said clamp member by said spike and having a rail-retaining portion extending over said flange, said second member having a portion thereof extending through the opening of said clamp member for said engagement with said head and the opening of said clamp member being of a size and shape to permit flexing of the clamp member without interference with said second member.

4. In a rail fastening, a tie plate, a rail on said tie plate and having a base flange, said tie plate having a shoulder thereon adapted to be engaged by said flange and an opening extending through said shoulder, a clamp member comprising a resilient plate extending over said shoulder and having its ends bearing respectively on said tie plate and flange, said clamp member having an opening therein overlying the opening of said tie plate, a fastener extending through said openings and having a holding portion in engagement with the clamp member and holding the latter in a flexed condition, and a second member disposed in the opening of said tie plate and having a rail-retaining portion overhanging said flange and a spacer portion adapted to be clamped between said shoulder and said holding portion of the fastener for limiting the initial flexing of the clamp member by said fastener, said spacer portion of said second member extending through the opening of said clamp member and being engaged by said holding portion and said opening of the clamp member being of a size and shape to permit flexing of the clamp member without interference with said second member.

5. A rail fastening as defined in claim 4 in which the opening of the clamp member is a slot of a length to permit shifting of the clamp member laterally toward the rail and relative to the fastener when the latter is in a partially driven position and wherein said second member is insertible into said slot and the opening of the tie plate when said clamp member is in such laterally shifted position.

6. In a rail fastening, a wood tie, a tie plate on said tie and having an opening therein, a rail on said tie plate and having a base flange, a resilient rail-holding clamp member having its ends bearing respectively on said tie plate and flange and also having an opening therein between said ends and overlying the opening of the tie plate, said opening of the tie plate including a substantially square portion and a round portion communicating therewith, a screw spike extending into the tie through the opening of the clamp member and through the round portion of the tie plate opening, said spike having a head engaging the upper side of the clamp member for holding the latter in a flexed condition against said tie plate and flange, and a rail guard having a

substantially square stem engaging in said square portion of the tie plate opening and a spacer portion extending upwardly through the opening of said clamp member and engaged by the head of the spike for limiting the initial flexing of the clamp member by the spike, said rail guard also having a holding portion overhanging said flange and said opening of the clamp member being of a size to permit free flexing of the clamp member without interference with said guard.

7. In a rail fastening, a wood tie, a tie plate on said tie and having an opening therein, a rail on said tie plate and having a base flange, a resilient rail-holding clamp member having its ends bearing respectively on said tie plate and flange and also having an opening therein between said ends and overlying the opening of the tie plate, said opening of the tie plate including a substantially square portion and a round portion communicating therewith, a screw spike extending into the tie through the opening of the clamp member and through the round portion of the tie plate opening, said spike having a head engaging the upper side of the clamp member for holding the latter in a flexed condition against said tie plate and flange, a rail guard having a substantially square stem engaging in said square portion of the tie plate opening and a spacer portion extending upwardly through the opening of said clamp member and engaged by the head of the spike for limiting the initial flexing of the clamp member by the spike, said opening of the clamp member being of a size to permit free flexing of the clamp member without interference with said guard and being elongated so as to extend over the rail flange, and a lateral rail-holding projection on said guard and disposed in the opening of said clamp member in overhanging relation to said flange.

8. In a rail fastening, a wood tie, a tie plate on said tie and having an opening therein, a rail on said tie plate and having a base flange, a resilient rail-holding clamp member having its ends bearing respectively on said tie plate and flange and also having an opening therein between said ends and overlying the opening of the tie plate, said opening of the tie plate including a substantially square portion and a round portion communicating therewith, a screw spike extending into the tie through the opening of the clamp member and through the round portion of the tie plate opening, said spike having a head engaging the upper side of the clamp member for holding the latter in a flexed condition against said tie plate and flange, a rail guard having a substantially square stem engaging in said square portion of the tie plate opening and a spacer portion extending upwardly through the opening of said clamp member and engaged by the head of the spike for limiting the initial flexing of the clamp member by the spike, said opening of the clamp member being of a size to permit free flexing of the clamp member without interference with said guard and being elongated so as to extend over the rail flange, and a lateral rail-holding projection on said guard and disposed in the opening of said clamp member in overhanging relation to said flange, said spacer portion having shoulder means thereon engaging the tie plate and the inner end of said rail-holding projection being engaged by the inner end of said opening of the clamp member.

9. In a rail fastening, a wood tie, a tie plate on said tie and having an opening therein, a rail

on said tie plate and having a base flange, a resilient rail-holding clamp member having its ends bearing respectively on said tie plate and flange and also having an opening therein between said ends and overlying the opening of the tie plate, said openings of the tie plate and clamp member each including a quadrangular portion and a rounded portion communicating therewith, a screw spike extending into the tie through the rounded portions of said openings and having a head engaging the upper side of the clamp member for holding the latter in a flexed condition against said tie plate and flange, a rail guard having a quadrangular portion disposed in the quadrangular portions of said openings and being engaged by the head of said spike for limiting the initial flexing of the clamp member by the spike, said opening of the clamp member being elongated to extend over the rail flange, and a rail-holding projection on said guard and disposed in the opening of said clamp member in overhanging relation to said flange, said opening of the clamp member being of a size and shape to permit flexing of said clamp member without interference by said guard.

10. In a rail fastening, a resilient clamp member having one end resting upon a rail flange and its opposite end bearing upon a tie plate and having an opening therein intermediate said ends, a fastening member and rail guard pin each extending through the clamp member and tie plate, the rail guard pin being clamped against the tie plate by the fastening member for limiting the vertical movement of the fastening member in one direction and said rail guard pin having means thereon for limiting movement of the rail in the opposite direction, the opening of said clamp member permitting flexing of the clamp member relative to said rail guard pin.

11. In a rail fastening, a resilient clamp member having one end resting upon a rail flange and its opposite end bearing upon a tie plate and having an opening therein intermediate said ends, a fastening member extending through the clamp member and tie plate and a rail guard pin directly engaged by and underlying the head of the fastening member and extending through the clamp member and into the tie plate, one side of said rail guard pin being headed to overlie the rail flange for limiting the vertical movement of the rail in one direction and said rail guard pin having shoulder means thereon engageable with said tie plate for limiting the vertical movement of the fastening member in the opposite direction, the opening of said clamp member permitting flexing of the clamp member relative to said rail guard pin.
